UNITED STATES PATENT OFFICE.

JOHN WALDHEIM, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed June 22, 1921. Serial No. 479,429.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

This invention relates to sound-deadening devices for typewriting machines. The invention is of the same general type as that disclosed in my co-pending applications, Serial No. 423,848, filed November 13, 1920 (now Patent No. 1,499,709, dated July 1, 1924), and Serial No. 466,820, filed May 4, 1921 (now Patent No. 1,519,645, dated December 16, 1924), and comprises a sound-deadening casing or hood for enclosing the noise-producing parts of a typewriting machine, while the keys and other parts of the machine used in its operation project from the casing or hood.

A feature of the device is the provision of a casing which may be readily attached to or detached from the machine. For this purpose, the casing comprises a cover hinged to a body part at the rear thereof, the latter having a front wall which provides a large opening into which the machine may be conveniently inserted, and hinged members or sections on the front wall which may be swung to close that part of the front opening not occupied by the machine.

A further feature of this invention is the provision of locking means for said hinged members. The hinged members are also provided with abutments for contacting with the posts of the typewriter frame to aid in holding the machine within the casing.

A further feature of the invention is the provision of a body part which terminates considerably below the lower surface of the platen, so that, when the cover part is swung upwardly, the platen-rotating mechanism and other parts associated with the platen will be readily accessible.

Various operating levers, such as the line-space handle, the carriage-return finger-piece, and the carriage-release lever, project forwardly from the typewriter carriage, and, since the body part of the casing terminates considerably below the platen, which is mounted in the carriage, these levers pro-

ject through a slot in the top wall or ceiling of the cover, which lies adjacent the levers, and this invention provides means for maintaining the slot closed to prevent leakage of sound therethrough.

A further feature of this invention is the provision of novel means for positioning the typewriter within the casing, said means comprising brackets fixed to the casing adjacent the base thereof and provided with openings large enough to receive the feet of the typewriting machine.

The typewriter is located accurately by means of both front and rear locators. The front locators, which are on the front wall of the hood, engage the front side posts of the typewriter framework, while said rear locators are preferably in the nature of sockets, into which the feet of the typewriting machine are inserted. If it be desired, the hood may be lifted together with the confined typewriting machine. The hands may be placed under the extensions of the hood or casing to lift the same, and the rear part of the typewriting machine will be raised by means of said sockets, which extend beneath the typewriter base; while the front part of the typewriter will be lifted by means of a horizontal bar, which extends from side to side of the casing at the front thereof and beneath the front or keyboard portion of the base of the typewriter.

Other features and advantages will hereinafter appear.

In the accompanying drawings, Figure 1 is a perspective view of the invention applied to an Underwood Standard typewriting machine.

Figure 2 is a view similar to Figure 1, but showing the cover in raised position and the pivoted members on the front wall swung to open position.

Figure 3 is a detail of the means for closing the slot through which the various operating levers project.

Figure 4 is a vertical section of the casing, the position of the typewriting machine being indicated in outline.

Figure 5 is a plan view of the body part of the casing, showing the means for positioning the machine within the casing.

The Underwood Standard typewriting machine comprises a main frame 10, and a forward extension 11 of said main frame in which are positioned banks of keys 12,

which, when depressed, operate key-levers 13 to swing type-bars 14 upwardly and rearwardly against a platen 15. Said platen is fixed upon a shaft or axle 16, journaled in the end walls 17 of a platen-frame 18 mounted in a carriage 20 supported on a front rail (not shown) and a rear rail 21. The carriage is provided with the usual pointer 27, operating over a scale 28. The platen may 10 be rotated by knobs or finger-wheels 30 fixed to the ends of shaft 16, or by the usual line-space mechanism, of which only the line-space handle 31 is shown. The carriage comprises, in addition to the forwardly-extending line-space handle 31, a forwardly-extending finger-piece 32, fixed thereto, for returning the carriage and a carriage-release lever 33.

The sound-deadening casing or hood comprises a body part 40 and a cover 41 hingedly connected to said body part at the rear, said body part comprising a rear wall 42 and side walls 43 in fixed relation to each other. With the cover raised, a typewriting machine is inserted in the body part, and, for this purpose, almost the entire front of the body part is open. The front opening is considerably larger than the width of the machine, so that, after the latter is positioned within the body part, there is still ample room at the sides to allow access to various mechanisms, such as the ribbon-winding and reversing mechanism at the sides of the machine.

To aid in rapidly positioning the machine within the casing, there are provided brackets 35, fixed to the rear wall 42 and extending along a base 36, which, in this instance, is of felt or other sound-deadening material, said brackets having openings 37 for receiving the usual rear typewriter feet 38. The brackets practically rest upon the base, thus avoiding excessive bending of the brackets downwardly and out of alignment by the weight of the machine when the latter is incorrectly placed on the brackets and strikes them with considerable force. The body part terminates at its upper side and front edges considerably below the lower 50 surface of the platen, so that, when the cover is raised, such mechanism as the finger-wheels 30 for rotating the platen will be readily accessible. The sides 43 are provided with lateral extensions or shelves 44, over 55 which the carriage travels to the left and right.

The cover 41 is hingedly connected at 50 to the upper edge of the rear wall 42 of the body part, said rear wall extending upwardly above the other walls of the body part to permit the cover to swing clear of the machine more easily. The cover comprises side walls 51, which rest upon the outer edges 44^a of shelves 44, a rear wall 52 in line 60 with rear wall 42, and a top wall or a ceiling

53 extending forwardly and downwardly and provided with a transparent plate 54 for permitting the interior of the casing to be viewed, said top wall terminating at the front in a slotted member 55, through which 70 various carriage levers extend, as will be described hereinafter. Said cover has a front wall 56, which extends downwardly slightly below the front edges of shelves 44 and lies adjacent the front of the main frame 10, just 75 above the banks of keys 12. Said front wall 56 is provided with an arcuate portion 57 which closes the opening 63 in the usual front plate 63^a on the main frame 10 leading to the type-bars, so that, when the cover is raised, access may be had to the type-bars to clean the types. The front wall 56 is also provided with cut-out portions 58 and 59 to expose a line-lock release key 64 and a ribbon-color shift-key 65 fixed to the front of 80 the main frame 10. When the cover is lowered, therefore, it will be seen that the machine is completely enclosed at the rear and sides, but only partly enclosed at the front. To close said front of the casing more effectively, there is provided, in addition to the front wall 56 at the upper part of the opening, a cross-bar 60 at the lower portion of the front opening between the sides 43, said cross-bar having extensions 61 to close that portion of the main frame of the typewriting machine from the base 36 to the guide-comb 66 in which the key-levers operate, and to support the front part of the machine 90 when the casing is lifted with the machine therein. There remain open the substantially rectangular portions of the casing-front contained between the wall 56, the bar 60, the sides of the casing, and the sides of the machine. To close these openings, there are 100 provided swinging members or doors 69, hinged at 70 to the front edges of the sides 43, said swinging members extending from the sides 43 to the sides of the machine, and from the base 36 to a point slightly 105 above the shelves 44, to completely fill the rectangular spaces above mentioned. The upper ends of doors 69 are provided with rearwardly-offset portions 71 for catching behind the front wall 56 of the cover, so that the doors are held in closed position after 110 the cover is applied. To lock the doors against opening, each is provided with a rotatable latch 72, pivoted to the rear of the door but operated by a knob 73 from the front, said latch having a rearwardly-offset portion 74, the ends of which may be beveled to readily catch behind the cross-bar 60. The edge of each swinging member which 115 contacts with the side of the machine is provided with a lip or fold 71^a of sound-deadening material, such as felt, to close the opening more effectively; said members carrying adjacent the same edges abutments 75 for contacting with the forward posts of the 120

125

130

main frame 10, said abutments co-operating with brackets 35 to hold the machine firmly within the casing.

The cross-bar 60 connects the two side walls 43, thus adding to the rigidity of the casing, and may be provided with slots 60^a through which levers, not shown, and other than the key-levers 13, may extend.

It is apparent from the description that the finger-pieces 31, 32 and 33 extend forwardly from the front bar 80 of the carriage, and are provided with substantially right-angular, upward projections passing through a longitudinal slot in member 55 near the front of the cover. The upper edge of said slot is formed by a guide-bar 82, which encloses the lower edge of the transparent plate 54, and, since this guide-bar is preferably of metal, it provides a durable bearing surface. The upwardly-extending projections of the finger-pieces are curved slightly rearwardly in an arc, the center of which is the hinge 50, thereby permitting the withdrawal and insertion of the finger-pieces in the slot when the cover is raised or lowered. Means are provided for closing all of the slot not occupied by the finger-pieces, said means comprising a fold or loop 83 of sound-deadening material, such as felt, whose ends are fastened between bars 84 to form a unit which is mounted adjacent the forward edge of the slot, a resilient tube 85 being inserted in the fold to spread the latter so as to fill the slot. The finger-pieces bear against guide-bar 82 and slide therealong in said slot during the normal travel of the carriage, said fold being yieldable forwardly to permit forward movement of certain of the finger pieces, such as the line-space handle, the resilient tube restoring the fold to initial position (Figure 3) as soon as the distorting force is removed.

It will thus be seen that all the ordinary typing operations may be carried out without disturbing the hood after it is once applied. By raising the cover, complete access may be had to the platen and its associated mechanism, and, by opening the front doors or swingable members, ample room is provided to give access to mechanism at the sides of the machine or to permit the machine to be withdrawn from the casing.

It will be understood that the machine is inserted into the casing from the top, that it is located relatively to the casing by the brackets or locators 35, and that the latter hold the casing relatively to the machine and prevent displacement thereof when the doors 69 are being manipulated.

As hereinbefore stated, the cover 41 rests on the outer edges 44^a of the shelves or lateral extensions 44 of the sides 43. Due to the weight of the cover, there is a tendency, especially when the casing is lightly built, to spread the sides 43 outwardly at the front

of the casing. To overcome any such tendency, however, the cover is provided with projections or flanges 90 (Figures 1 and 2) to engage the outer edges 91 of the extensions 44 when the cover is in its lowered position.

The casing may be lined with any suitable material to more effectually deaden the sound emanating from the machine.

Variations may be resorted to within the scope of the invention, and portions of the improvements may be used without others.

Having thus described my invention, I claim:

1. A sound-deadening casing for a typewriting machine comprising a frame having a keyboard extension, said casing comprising a body part and a cover hinged at the rear to said body part, said body part comprising a rear wall and side walls, the front of said body part being open to permit the insertion of the typewriting machine in said casing, and doors hinged at their outer edges on said casing and swingable inwardly to close the front of the casing at each side of the machine, said doors having at their inner edges cushion devices to engage the machine frame at each side of the keyboard extension and seal the openings between the inner edges of the doors and the machine frame.

2. A sound-deadening casing for a typewriting machine comprising a frame having a keyboard extension, said casing comprising a body part and a cover hinged at the rear to said body part, said body part comprising a rear wall and side walls, the front of said body part being open to permit the insertion of the typewriting machine in said casing, and doors hinged at their outer edges on said casing and swingable inwardly to close the front of the casing at each side of the machine, said doors having at their inner edges cushion devices to engage the machine frame at each side of the keyboard extension and seal the openings between the inner edges of the doors and the machine frame, and abutments having contact portions to engage the machine frame and so shaped as to assist in positioning the machine frame in a lateral direction.

3. A sound-deadening casing for a typewriting machine, said machine comprising a main frame, and a forward extension of said frame in which are positioned banks of keys, said casing comprising a body part and a cover part, said body part comprising a rear wall and side walls, the front of said body part being open to permit the insertion of the typewriting machine, said forward extension projecting outside of said casing, and a depending front wall carried by said cover part for closing that portion of the front opening between the cover and the banks of keys, said typewriting machine

having a line-lock release key and a ribbon color-shift-key mounted on said frame above said keys, said depending front wall having cut-out portions to clear said release key and shift-key.

4. A sound-deadening casing for a typewriting machine, said machine comprising a main frame and a forward extension of said frame having a typewriter keyboard, 10 said casing comprising a body-part and a cover-part, said body-part comprising a rear wall and side walls, the front of said body-part being open to permit the insertion of the typewriting machine, said forward extension projecting out of said casing, and swingable doors pivotally mounted to the front edges of the side walls, the edges of said doors being provided with extensions of sound-deadening material to engage the 15 sides of the typewriter frame to prevent the escape of sound between said edges and the frame, said side walls having at their tops lateral extensions to support the cover-part when said cover is closed, said cover having 20 at its opposite ends, adjacent the edge of each lateral extension, a lug engaging the edges of said lateral extensions, to prevent the spreading of the upper portion of said side walls, and said cover being provided 25 with a downwardly-extending front portion formed to co-operate with said side walls, said swinging doors and said machine frame to provide a casing having a closed front.

5. A sound-deadening casing for a typewriting machine having a frame and supporting feet, said casing comprising a rear wall and side walls and having means for positioning said machine within said casing, 30 said means comprising forwardly-projecting brackets fixed to said rear wall and having openings for receiving the rear typewriter feet, and abutments hinged on said side walls to be swung into engagement with said frame at the front thereof.

6. A sound-deadening casing for a typewriting machine comprising a frame having a keyboard extension, said casing comprising a body part and a cover hinged at the rear to said body part, said body part 40 comprising a rear wall and side walls, the front of said body part being open to permit the insertion of the typewriting machine in said casing, and doors hinged at their outer edges on said casing and swingable inwardly 45 to close the front of the casing at each side of the machine, said doors having at their inner edges sound-deadening material to engage the machine frame at each side of the keyboard extension and effect a sound- 50 sealing fit therewith, means effective at the upper edges of the doors for locking the latter in closed position, comprising co-operative provisions such that the closing 55 of the cover, when said doors are closed, will 60 effect locking of the latter, and means upon 65

the rear wall of the casing and the doors for holding said machine in said casing in operable position.

7. A sound-deadening casing for a typewriting machine comprising a main frame, 70 a forward keyboard extension of said frame and feet for supporting the main frame, said casing comprising a body part and a cover, said body part comprising a rear wall, side walls, the front of said body part being open to permit the insertion of the typewriting machine, said forward extension projecting outside of said casing when the insertion has been completed, doors hinged on 75 said casing and swingable to effective position for closing that portion of the front opening between said side walls and the sides of said frame, means for closing the opening between the main frame and a surface upon which said feet rest, said means comprising a vertical plate secured at its ends to said side walls, provided with a substantially central upwardly extending portion and laterally-extending portions on 80 either side thereof closing the lower portion of the space between the machine frame and said side walls, and means for locking the doors in effective position, said last-named means comprising a latch carried by each 85 of said doors and operable to engage said vertical plate.

8. A sound-deadening casing for a typewriting machine having a carriage, said casing comprising a body part and a cover, the body part comprising side walls, a front wall and a rear wall, the front wall having an opening to permit the insertion of the machine into the casing, said opening extending to the top of said side walls, said side walls having substantial upper overhanging lateral extensions to form with the cover pockets to accommodate the travel of the carriage beyond the vertical position of said side walls, said lateral extensions forming supports for said cover when in its closed position, and a finger depending from each side of, and unitary with, said cover near its front to engage the outer edges of the upper lateral extensions adjacent the ends of said cover, when the cover is in its lowered position, and prevent lateral spreading of the upper portions of said side walls.

9. A sound-deadening casing for a typewriting machine, said casing comprising a back wall, side walls, a front wall having an opening through which the keyboard of the machine projects, said walls constituting the body portion of the casing, and supporting means to receive the weight of the machine when the casing is lifted with the machine in its upright position, said supporting means comprising brackets extending inwardly from said body portion to engage the machine at its rear, and a cross-member extending across the bottom of said body por-

- tion at the front thereof, beneath the machine frame.
10. A sound-deadening casing for a type-writing machine, said casing comprising a back wall, side walls, a front wall having an opening through which the keyboard of the machine projects, said walls constituting the body portion of the casing, and supporting means to receive the weight of the machine when the casing is lifted with the machine in its upright position, said supporting means comprising brackets extending inwardly from said portion to engage the machine at its rear, and a cross-member extending across the bottom of said body portion at the front thereof, beneath the machine frame, said cross-member being the portion of the front wall beneath the opening in the latter.
- 15 11. A sound-deadening casing for a type-writing machine, said casing comprising a body part and a cover for said body part, the body part comprising side walls, a rear wall and a front wall, the front wall having an opening therein to enable the machine to be inserted into the casing, and two doors pivoted at the front wall and on the forward ends of the side walls of said casing, said doors being effective to close the opening in the front wall not occupied by the machine, the free ends of the doors engaging the machine, said cover comprising a front wall, and rearwardly-offset projections on said doors to engage behind the front wall of the cover to hold the doors closed when the cover is in its lowered position, and permitting the doors to be flush with the front wall of the cover when the casing is closed.
- 20 12. A sound-deadening casing for a type-writing machine comprising a main frame having a forwardly-extending keyboard extension having key-levers therein and a key-lever-guiding comb-plate at the front of the main frame, said casing comprising a body part and a cover, the body part comprising two side walls, a rear wall and a front wall, the front wall having an opening to enable the machine to be placed within the casing with the keyboard extension of said machine protruding from said casing through the opening in the front wall, said front wall including a cross-bar disposed beneath and near the front of said machine and having a substantially central upward extension to close the space beneath the comb-plate and lateral portions on either side of said central extension to form front wall sections between the machine frame and the side walls of the casing below the machine frame.
- 25 13. A casing for a typewriting machine comprising a forwardly-extending keyboard section, said casing comprising a front wall through which the keyboard section protrudes and having an opening above said keyboard section, three pivoted elements to close the openings in the front wall at the sides of and above said keyboard section, said elements comprising a cover having a front wall to close the opening above said keyboard section, and two doors pivoted on said casing to close the openings at the sides of said keyboard section and to co-operate with the front wall of the cover to close the space not occupied by the machine in the opening in the front wall.
- 30 14. A sound-deadening casing for a type-writing machine, the typewriting machine comprising a forwardly-extending keyboard section having key-levers therein, said casing comprising a body part and a cover, the body part comprising two side walls, a rear wall and a front wall, the front wall having an opening to enable the machine to be placed within the casing with the keyboard section protruding from said casing and through the opening in the front wall, a cross-bar forming part of the front wall and disposed beneath said machine to close the space beneath the key-levers and enabling the casing to raise the front part of the typewriting machine when the casing is lifted and the cross-bar is brought into engagement with the machine, and carriage-locators projecting from the rear wall of said casing to engage the typewriter feet, said locators extending beneath the rear portion of the typewriter base to engage and raise the same when the casing is lifted.
- 35 15. The combination of a sound-deadening casing, and a typewriting machine therein, said casing comprising an open bottom body part and a cover, means being provided upon said casing to engage and locate the typewriting machine and to raise the same when the casing is lifted, said means comprising brackets upon the rear wall of the casing engaging the rear feet of the typewriting machine and a cross-bar beneath and near the front of said machine forming a part of the front wall of said casing and engaging and supporting said machine when the casing is lifted.
- 40 16. In a sound-deadening casing for a typewriting machine, a vertical plate extending beneath the keyboard-extension of the frame immediately to the front of the front posts, and having between the sides of said extension an upwardly-projecting portion provided with vertical slots.
- 45 17. A sound-deadening casing for a type-writing machine, said machine comprising a main frame and a forward extension of said frame having a typewriter keyboard, said casing comprising a body-part and a cover-part hinged thereto, said body-part comprising a rear wall and side walls, the front of said body-part being open to permit the insertion of a typewriting machine, said forward extension projecting out of said casing, said side walls being provided at their

- top with laterally-extending portions to support the cover in closed position, said cover being provided on its opposite ends with lugs, engaging the edges of the lateral extensions to prevent the lateral displacement of the upper portions of the side walls when the cover is closed, swingable doors pivotally mounted at the front edges of the opposite side walls having their inner edges 5 provided with extensions of sound-deadening material, to engage the sides of the typewriter-frame and prevent the escape of sound between said edges and said frame, said cover having a downwardly-extending 10 portion on its front face, arranged to cooperate with said typewriter-frame and with said doors, to provide a closed front for said casing, and a bar fixed to and joining the bases of the side walls at their front, to 15 prevent the displacement of the lower portion of said side walls and provide means whereby the swingable doors may be held 20 in closed position.
18. A sound-deadening bottomless casing 25 for a typewriting machine, comprising a body and a cover, and combined locating and lifting devices for the feet of the ma-
- chine to position the same in the casing, said devices mounted on the walls of the cover normally below the machine frame and engaging the frame when the cover is lifted with respect to the machine as the latter stands in typing position. 30
19. A sound-deadening bottomless casing for a typewriting machine, comprising a body fitting loosely about the machine to rest upon the supporting surface therefor, a cover for the body, and a connection between the body and the machine to lift the machine as the latter stands in typing position with the body when the body is lifted. 35
20. The combination with a typewriting machine, of a sound-deadening bottomless casing therefor having an open bottom, and a loose connection with the machine to constrain the machine as the latter stands in typing position to lift with the casing and to permit the casing to engage the supporting surface for the machine. 40 45
